UNITED STATES PATENT OFFICE.

CHARLES JARVIS, OF NEW YORK, N. Y.

IMPROVEMENT IN LINE-CONNECTORS.

Specification forming part of Letters Patent No. 122,021, dated December 19, 1871.

To all whom it may concern:

Be it known that I, CHARLES JARVIS, of the city, county, and State of New York, have invented a new and useful Improvement in Line-Connectors, of which the following is a specification:

My invention consists in making an elongated piece of wood or metal with a hole at each end and a projecting pin at one end of the same, said block having ears at one side for the reception of a bar between them, and relates to the fastening together the two ends of a rope to serve as a splice.

Figure 1 is a clear view of the connector. Fig. 2 is a view of the connector when in use.

The hole A is for the securing of one end of

the rope. The hole B is for the reception of the remaining end after the line is set out; the point C to act as a turn for the rope; the bar D to act as a catch or clamp for the same; the ears E E and the pin F for the securing of the bar D to the block.

I claim—

The arrangement of the block with holes at each end, and a projecting pin at one end of the same and two ears at one side of the block, between which is inserted a bar secured by a pin, and to be used for the purpose of securing ropes and lines, substantially in the manner set forth.

Witnesses: CHARLES JARVIS.

B. F. KEMP,
G. H. DEGRAW.
